UNITED STATES PATENT OFFICE.

JACOB A. COHEN, OF BROOKLYN, NEW YORK.

SASH-CORD ANCHOR.

Application filed October 30, 1928. Serial No. 316,028.

This invention relates to fastening devices, and has particular reference to an improvement in means for anchoring sash cords to window sashes.

5 Primarily, the invention comprehends an anchoring device of this nature which facilitates the securement of the sash cord to the sash and which enables the attachment to be made or the cord released without the necessity of removing the sash from its frame or disturbing the molding strip forming a part of the frame.

More specifically, the invention contemplates in combination with a window sash 15 having the usual sash cord receiving groove in the side edge of the stile and a recess communicating with the groove and opening through the inner face of the stile, a means for anchoring the sash cord to the sash which 20 consists of a plate detachably secured to the inner face of the stile and covering the recess, together with an adjustable element carried by and projecting from the plate inwardly into the pocket for embracingly and 25 clampingly engaging the sash cord, which element is further provided with externally disposed means for releasing the same.

Other objects of the invention reside in the comparative simplicity of construction of the 30 device, the economy with which it may be produced and installed without material alteration to the sash structure and the general efficiency derived therefrom.

With the above recited and other objects in 35 view, reference is had to the following description and accompanying drawings, in which there is exhibited one example or embodiment of the invention, while the claims define the actual scope of the same.

40 In the drawings:

Figure 1 is a fragmentary inner face view of a window sash mounted in its frame and equipped with a sash cord anchoring device constructed in accordance with the invention.

45 Figure 2 is a fragmentary perspective view illustrating the manner in which the sash cord is attached.

Figure 3 is a similar view illustrating the 50 sash cord attached by an anchoring device constructed in accordance with the invention.

Referring to the drawings by characters of 55 reference, A designates a window sash including the usual stile B and mounted in the window frame C between the parting strip D

and the molding strip E. The side of the stile B is provided with the usual sash cord receiving groove F which communicates at its lower end with a recess G opening through 60 the inner surface of the stile. The means for anchoring the sash cord to the sash consists of a plate 5 which is attached to the inner surface of the stile B by screws or other fastening elements 6 so as to cover and conceal from 65 view the recess G. A sash cord clamping element designated generally by the reference character 7 is carried by and projects from the plate 5 inwardly into the recess or pocket G. The element 7 is preferably in the nature 70 of a resilient strip of material cut, bent and formed to provide a split tubular intermediate section 8 of slightly lesser internal diameter than the diameter of the sash cord H. The element 7 further includes ears 9 75 extending from the split tubular portion 8 and having laterally bent terminals 10 which are designed to be disposed in flat contact with the inner face of the plate 5. Bolts 11 extend through aligned openings in the plate 80 and in the terminals 10 and receive nuts 12. The bolts are provided with externally disposed kerfed heads 13 by means of which the clamping element 7 may be loosened from the exterior to release the sash cord H. 85

In use, when it is desired to renew or replace the sash cord H, the bolts 11 and nuts 12 are loosened to release the clamping element 7 from the end of the cord H. The screws or fastening elements 6 are then removed and 90 the sash cord H is trained downwardly through the groove F and outwardly through the recess or pocket G which is exposed by the removal of the plate 5. The terminal of the sash cord H is then inserted within the tubular portion 8 of the clamping element 7 and the bolts 11 are tightened, as illustrated in Figure 2. The only remaining operation is now to replace the plate 5, at the same time inserting the element 7 in the recess or pocket 95 100 and re-applying the screws or fastening elements 6. Obviously, the operation is accomplished without the necessity of receiving the molding strip E or displacing the sash A from the window frame. 105

The term "sash cord" is used in its broadest sense, and comprehends a chain cable or any equivalent flexible element which may perform its function.

What is claimed is:

110 1. The combination with a window sash having a sash cord receiving groove in the

stile and a recess communicating with said groove and opening through the inner face of the stile, of means for anchoring the sash cord to the sash comprising a plate detachably secured to the inner face of the stile and covering the recess and an element carried by and projecting from the plate inwardly of the recess for clamping engagement with the sash cord, said element having externally disposed means for releasing the same from the sash cord.

2. A sash cord anchoring means including in combination with a window sash having a sash cord receiving groove in the side face of the stile and a recess communicating with said groove and opening through the inner face of the stile, of a plate detachably secured to the inner face of the stile for covering the recess and an externally releasable element carried by and projecting inwardly from the

plate into the recess for embracing and frictionally clamping the terminal of the sash cord.

3. A sash cord anchoring means including in combination with a window sash having a sash cord receiving groove in the side face of the stile and a recess communicating with said groove and opening through the inner face of the stile, of a plate detachably secured to the inner face of the stile for covering the recess and an element carried by and projecting inwardly from the plate into the recess for embracingly engaging the terminal of the sash cord, said element having externally disposed means for releasing the same and for attaching it to the plate.

Signed at New York, in the county of New York and State of New York, this 27th day of October, A. D. 1928.

JACOB A. COHEN.
